UNITED STATES PATENT OFFICE.

CHARLES E. CATHER, OF WORCESTER, MASSACHUSETTS, ASSIGNOR TO UNITED STATES ENVELOPE COMPANY, OF SPRINGFIELD, MASSACHUSETTS, A CORPORATION OF MAINE.

METALLIC FASTENER FOR MERCHANDISE-ENVELOPS.

1,235,289.

Specification of Letters Patent. Patented July 31, 1917.

Application filed December 3, 1915. Serial No. 64,912.

To all whom it may concern:

Be it known that I, CHARLES E. CATHER, a citizen of the United States, residing at Worcester, in the county of Worcester and 5 Commonwealth of Massachusetts, have invented a new and useful Improvement in Metallic Fasteners for Merchandise-Envelops, of which the following is a specification, accompanied by drawings forming a 10 part of the same.

My present invention relates to that class of merchandise envelops in which the sealing flap is secured to the body of the envelop by a pair of bendable tongues adapted to 15 be inserted through an opening in the seal flap and bent down upon the outer surface of the seal flap.

In the accompanying drawings I have shown a metallic fastener applied to a merchandise envelop embodying the novel features of my invention which are hereininafter described and specifically pointed out in the appended claims.

Referring to the drawings,

25 Figure 1 is a front view of a merchandise envelop having a metallic fastener attached to the body thereof, said envelop being represented in an extended position.

Fig. 2 is a perspective view of the seal 30 flap end of the envelop and having the bendable tongues of the metallic fastener raised in position to be inserted through the opening in the seal flap.

Fig. 3 is a perspective view of the seal 35 flap end of the envelop showing the seal flap closed and secured by the metallic fastener.

Similar reference characters refer to similar parts in the different figures.

40 In the accompanying drawings, 1 denotes the body portion of a merchandise envelop, 2 the sealing flap by which the open end of the envelop is closed. Said sealing flap is provided with an opening 3 adapted 45 to receive a pair of bendable tongues securely attached to the body portion of the envelop.

In the present instance the metallic fastener is represented as having a pair of 50 bendable tongues 4, 5, projecting in opposite directions from a central plate 6, said central plate having at its ends laterally extending arms 7 which are attached to the body portion of the envelop in the usual 55 and well known manner. In the completed

envelop the bendable tongues lie flat against the body of the envelop as represented in Fig. 1. In the operation of closing the envelop the bendable tongues are bent upwardly as shown in Fig. 2, bringing their tips approximately together to enable both tongues to be passed through the opening 3, when the tongues are again bent down upon the outer surface of the seal flap, as represented in Fig. 3.

My present invention is not concerned with the method of attaching the bendable tongues to the body portion of the envelop. In the present instance I have shown them as attached by a method now in common 70 use, but other means of attachment may be employed without departing from the spirit of my invention, which relates solely to the means for facilitating the bending of the tongues down upon the outer surface of the 75 seal flap. To facilitate the bending of the tongues the free end of each of the bendable tongues 4 and 5 is provided with laterally projecting wings 8 and 9. Said wings 8 and 9 are extended from opposite 80 edges of the tongues 4 and 5, as represented in Figs. 2 and 3. The projecting wings 8 and 9 enable each of the tongues to be engaged by the finger and pressed in opposite directions in order to fold them upon the 85 outer surface of the seal flap. When the bendable tongues 4 and 5 have been passed through the opening 3 and the seal flap closed down into contact with the body of the envelop, pressure may be readily applied in opposite directions to the wings 8 and 9, however closely the free ends of the 90 bendable tongues may have been brought together.

I claim,

1. A metallic fastener for envelops, comprising a central plate provided with means for attaching the same to the body of an envelop, and a pair of parallel bendable tongues extending from opposite sides of 100 said central plate, each of said tongues being provided with a laterally extended wing at its free end, said wings projecting in opposite directions from the oppositely disposed edges of said tongues.

2. A metallic fastener for envelops, comprising a pair of oppositely disposed bendable tongues, one of said tongues having an integral wing extending from one of its edges, and the other of said tongues having 110

an integral wing extending from one of its edges in the opposite direction to said first named wing and in substantially the same plane as said first named wing.

5. A metallic fastener for envelops, comprising a pair of oppositely disposed bendable tongues of equal length, each of said tongues having an integral wing extending

laterally from its upper end, said wings being disposed on opposite sides of said 10 tongues.

Dated this 27th day of November 1915.

CHARLES E. CATHER.
